[57] CLAIM

The ornamental design for a face rejuvenator, as shown and described.

DESCRIPTION

FIG. 1 is an isometric view of a face rejuvenator;
FIG. 2 is a front elevational view of the embodiment shown in FIG. 1;

FIG. 3 is a right side elevational view of the embodiment shown in FIG. 1, thereof;

FIG. 4 is a rear elevational view of the embodiment shown in FIG. 1, thereof;

FIG. 5 is a top plan view of the embodiment shown in FIG. 1, thereof; and,

FIG. 6 is a bottom plan view of the embodiment shown in FIG. 1, thereof.

The broken lines showing of a portion of the face rejuvenator in FIGS. 1 through 6 are for illustration purpose only and forms no part of the claimed design.
